UNITED STATES PATENT OFFICE

152,141

DESIGN FOR A CARGO CONTAINER

Marion B. Crawford, Western Springs, and Edwin C. Mitchell, Oak Park, Ill., assignors to United Air Lines, Inc., Chicago, Ill., a corporation of Delaware

Application March 20, 1946, Serial No. 127,715

Term of patent 7 years

(Cl. D58—4)

To all whom it may concern:

Be it known that we, Marion B. Crawford and Edwin C. Mitchell, citizens of the United States, residing at Western Springs, in the county of Cook and State of Illinois, and Oak Park, in the county of Cook and State of Illinois, respectively, have invented a new, original, and ornamental Design for Cargo Container, of which the following is a specification, reference being had to the accompanying drawing, forming a part thereof, in which:

Figure 1 is a perspective view of a cargo container, embodying our new design;

Fig. 2 is an end elevational view of the cargo container shown in Fig. 1; and

Fig. 3 is a side elevational view thereof.

We claim:

The ornamental design for a cargo container, substantially as shown.

MARION B. CRAWFORD.
EDWIN C. MITCHELL.
